UNITED STATES PATENT OFFICE

2,512,760

VIBRATION ACTUATED TOY

Harry Y. Armstrong, Syracuse, N. Y.

Application May 8, 1946, Serial No. 668,041

3 Claims. (Cl. 46—47)

1

This invention relates to improvements in toys, and has as an object an amusement device particularly economical to manufacture, simple to operate, and which will afford considerable amusement.

More specifically, the invention has as an object a device of the character referred to comprising two parts which are cooperable upon relative rotatable movement to produce a sound closely imitating a canary bird, and one of the parts being provided with a rotating member, rotation of which is effected by the vibratory action created when the parts are rotated in frictional engagement.

The invention consists in the novel features and in the combinations and constructions hereinafter set forth and claimed.

In describing this invention, reference is had to the accompanying drawings in which like characters designate corresponding parts in all the views.

Figure 1 is a vertical, sectional view of a device embodying my invention.

Figure 2 is an end elevational view of the structure shown in Figure 1.

Figure 3 is a view, similar to Figure 1, with the plug member shown in side elevation.

Figure 4 is an end elevational view of the plug member.

The device consists of a block and plug cooperable upon relative rotation to produce a relatively high pitch sound of varying frequency which closely imitates the chirping of a song bird, such as a canary bird.

The block 10 is formed with a tapering socket 11. Preferably, the inner end of the socket communicates with a cylindrical passage 12 extending through the block. The block and the plug 13 may be formed of hard wood, or the like, and if formed from wood, the axis of the tapering socket 11 preferably extends parallel to the grain of the wood.

The plug 13 is provided with an end portion having a plurality of ribs 14 extending on a taper complementary to the taper of the socket 11. As here shown, the ribs 14 are provided by forming the plug from square stock, although it will be apparent that the plug may be formed from round stock and the end portion grooved to provide ridges or ribs.

When the plug 13 is inserted in the socket 11, pressed into frictional engagement therewith and rotated, the ribs 14 are cooperable to effect a vibratory movement which produces the sound effect previously referred to. The sound effect

2

may be augmented by forming the plug with a passage 15 extending lengthwise of the plug and opening through the tapered end portion between a pair of the ribs 14.

5 A stem 18 is fixedly secured at one end to the block 10 and a rotating member 19, in the nature of a cardboard disk, is journaled on the outer end of the stem, as by being freely mounted upon a pin 20. The vibratory effect produced by the 10 block 10 and the plug 13 causes vibration to travel through the stem 18 and this, in turn, effects rotation of the disk 19 after the manner of the well known Indian stick, or whirligig toys.

I have found that the vibration transmission is 15 particularly effective if the stem 18 is tightly secured in a slot extending transversely across the end of the plug opposite the socket 11. With this arrangement, the disk 19 is caused to rotate rapidly simultaneously with the production of the sound effect.

The device is particularly suitable for small children in that it is easily manipulated and the structure is such as not likely to cause any harm to children.

25 What I claim is:

1. A toy comprising a cooperating block and plug formed of wood or the like, said block being provided with a tapering socket, and said plug having a tapered end portion adapted to be rotated in frictional engagement with said socket, said end portion being formed with a taper complementary to the taper of said socket, a plurality of longitudinal ribs on said tapered end portion, and a longitudinal passage extending through 35 said plug and opening through the side wall of said tapered end portion.

2. A toy comprising a cooperating block and plug formed of wood or the like, said block being provided with a tapering socket and said plug 40 being formed with a tapered end portion adapted to be rotated in frictional engagement with said socket and having a taper complementary to the taper of said socket, a stem rigidly secured to the block and extending laterally therefrom, and 45 a member freely journaled on the outer end of said stem.

3. A toy comprising a cooperating block and plug formed of wood or the like, said block being provided with a tapering socket in one end and 50 said plug being formed with a tapered end portion complementary to the taper of said socket and adapted to be rotated in frictional engagement therewith, a plurality of longitudinal ribs extending on said tapered end portion of the plug, said 55 block being formed at the opposite end thereof

with a recess extending transversely of the axis of said socket, a stem member fixedly secured in said recess and extending laterally from the block, and a movable member freely journaled on the outer end of said stem.

HARRY Y. ARMSTRONG.
